UNITED STATES PATENT OFFICE.

HUGO NELSON, OF MINNEAPOLIS, MINNESOTA.

DESIGN FOR AN ARTICLE OF JEWELRY—NAMELY, A PIN, BROOCH, RING, OR ARTICLE OF SIMILAR NATURE.

60,257.

Specification for Design.

Patented Jan. 17, 1922.

Application filed March 12, 1921. Serial No. 451,817. Term of patent 14 years.

To all whom it may concern:

Be it known that I, HUGO NELSON, a citizen of the United States, residing in Minneapolis, county of Hennepin, and State of Minnesota, have invented a new, original, and ornamental Design for an Article of Jewelry—namely, a Pin, Brooch, Ring, or Article of a Similar Nature—of which the following is a specification, reference being had to the accompanying drawings, forming part hereof.

In the drawings:

Figure 1 is an edge view of a ring embodying the design on the periphery thereof;

Figure 2 is a side view of a ring showing the design as applied to the side of the ring.

In the drawings, the body portion 3 of the ring is of the color of platinum (white gold being preferably employed for this purpose) and is engraved with the design 4 comprising a suggestion of flower-like portions 5 at spaced intervals. The flower-like portions 5 are alternately of a green color and of a red color (green and white gold being pref-

erably employed for this purpose). The portions of the ring intermediate the flower-like portions 5 bear the leaf-like engravings 6 which are of the color of platinum, similarly to the body of the ring.

It is to be understood that the details of the coloring of the engraved portions may be varied without departing from my invention which resides in the contrast between the green, the red and the white colored portions of the article. While the design is shown as embodied in a ring it is to be understood that the application of the design is not limited to rings of the type shown, as it may obviously be embodied in other articles of jewelry, such as solitaires, bar pins, scarf pins, bracelets, and the like.

I claim:

The original design for an article of jewelry, namely, a pin, brooch, ring, or article of similar nature.

In witness whereof, I have hereunto set my hand this 8th day of March, 1921.

HUGO NELSON.
